UNITED STATES PATENT OFFICE.

ELIJAH M. BOSLEY, OF ST. LOUIS, MISSOURI.

SECTIONAL BOILER.

No. 872,495.

Specification of Letters Patent.

Patented Dec. 3, 1907.

Application filed February 9, 1907. Serial No. 356,585.

To all whom it may concern:

Be it known that I, ELIJAH M. BOSLEY, a citizen of the United States, residing at St. Louis, Missouri, have invented a certain new and useful Improvement in Sectional Boilers, of which the following is a full, clear, and exact description, such as will enable others skilled in the art to which it appertains to make and use the same, reference being had to the accompanying drawings, forming part of this specification, in which—

Figure 1 is a vertical longitudinal sectional view through a boiler embodying the features of my invention; Fig. 2 is a detail sectional view of the outer end of one of the tubes which admit air above the grate when the main draft door is closed; Fig. 3 is a vertical sectional view taken on the line 3—3 of Fig. 2; and Fig. 4 is a horizontal sectional view taken on the line 4—4 of Fig. 3.

This invention relates to boilers for heating systems, and particularly to the type of boiler described in my pending application Serial No. 315,355, filed May 5, 1906, although some of the novel features herein described can be embodied in other types of boilers without departing from the spirit of my invention.

One object of the invention herein described is to provide a down-draft sectional boiler having vertical flues leading from the combustion chamber beneath the grate to a horizontal flue at the upper portion of the boiler which leads to the smoke pipe.

Another object of my invention is to provide a sectional steam boiler having a circulation on the water line so that all of the sections of the boiler will be heated uniformly. And still another object of my invention is to provide a down-draft sectional boiler provided with means for creating combustion above the grate during the suspension of the draft from the main draft door. Other desirable features of my boiler will be hereinafter described.

Referring to the drawings which represent the preferred form of my invention, A designates the intermediate sections of the boiler, all of which are of the same shape, and B and C designate, respectively, the front and rear sections of the boiler. Each of the intermediate sections has a hollow water base 1 which connects the water legs 2, as shown in Fig. 3, and also a hollow water crown 3 ex-

tending over the grate and provided with hollow depending portions 4 which extend downwardly on each side of the combustion chamber beneath the grate. The depending portions 4 of the crown are of approximately the same width as the water legs 2, and are connected to said water legs by hollow contracted webs 5, as shown in Fig. 4, so that the portion of each section of the boiler adjacent the combustion chamber is approximately H-shaped in cross section. The portion 3 of the hollow water crown is connected to the water chamber 6 at the upper end of each section by a vertically-disposed water chamber 7 that forms the inner sides of the horizontal flues 7^a which extends longitudinally of the boiler to the smoke pipe 8 provided with a check damper 8^a, the outer sides of said flues being formed by the end walls 9 of the hollow webs 5, said webs extending upwardly and connecting the portion 3 of the hollow water crown with the water chamber 6, as shown in Fig. 3.

When the sections of the boiler are placed together the spaces between the contracted webs 5 of each section will form vertically-disposed flues 10 that lead from the combustion chamber beneath the grate to the horizontally extending flues 7^a that lead to the smoke pipe, the fire traveling through these flues as indicated by the arrows in Figs. 1 and 3, and thus heating the water in the crown, in the water legs, in the water chamber 6, and in the water base 1.

Each section of the boiler is provided with a steam dome 12 and the sections are connected with each other at their upper and lower ends by means of nipples 13 and 14, respectively, so that the water can circulate through all of the sections of the boiler, the nipples 13 connecting the water chambers 6 and the nipples 14 connecting the water bases 1. The grate is formed by a plurality of hollow sections 15, each of said sections being connected by means of nipples 16 to the front and rear sections of the boiler so that the water also circulates through the grate. As shown in Fig. 1, the nipples which connect the water grate sections to the front and rear sections of the boiler, are expanded into the inner walls 17 of said front and rear sections, and the outer walls 18 of said front and rear sections are provided with removable plugs 19 in alignment with said nipples,

thereby permitting an expanding tool to be inserted into said front and rear sections to expand said nipples.

The advantage of a construction of this character is that it enables the grate sections to be renewed with very little trouble, the plugs 19 being located in the outer walls of the front and rear sections so that they are not subjected to fire and accordingly, can be removed easily. The grate, as shown in Fig. 1, is inclined upwardly from the front to the rear of the boiler so as to cause the water to circulate upwardly through the boiler. The main draft door 20 is located above the grate and admits air above the fuel on the grate, thus causing the fire to pass downwardly and play directly on the water bases 1 of the sections, the fire then passing up the vertical flues 10 and out through the horizontal flues 20 7^a to the smoke pipe. By constructing the sections of the boiler so that vertical flues 10 are formed between the water legs I am enabled to build a very short boiler as it is not necessary to use a number of sections at the rear of the inner end of the grate so as to provide a passageway through which the fire travels from the combustion chamber to the horizontally-disposed flues that lead to the smoke pipe. Another desirable feature of a construction of this character is that the vertical flues tend to draw the fire downwardly against the water bases and also divide the flame so that each section of the boiler will get an equal division of heat. One feature 35 of my invention which I believe is new in down-draft sectional boilers is providing means for creating combustion above the grate when the main draft door is closed so as to consume the gases which rise from the 40 coal. This I accomplish by providing the boiler with a plurality of tubes 21 arranged horizontally over the grate and provided with perforations 21^a, preferably at their rear ends, through which air is admitted 45 above the grate, the front ends of said tube extending through the front section of the boiler and being preferably provided with dampers 22 which permit the quantity of air which passes through said tubes to be varied. When the main draft door 20 is closed 50 air passes through these tubes 21 and becomes heated to a great temperature and this heated air mixing with the free gases that rise from the fuel produces combustion above the grate so that the underneath side of the crown 3 is subjected to great heat.

This boiler can be used for either a steam or hot water system as each section is provided with a steam dome 12, as previously 55 described. The boiler is herein illustrated as being used for a steam heating system and as there is a water connection between the water chambers 6 of the sections, I obtain a circulation on the water line through all of 60 the sections of the boiler, thereby causing all

of the sections to be heated uniformly. In the sectional boilers which have heretofore been in use the water did not circulate directly through one section into the other at the top of the boiler so that it was necessary to have a grate extending underneath all of the sections to cause the water therein to be heated to a uniform temperature.

In my boiler the water circulates on the water line from one section into the other as well as through the water bases so that I am able to use a very short grate, namely, one that extends underneath only a few of the sections.

Having thus described my invention, what I claim as new and desire to secure by Letters Patent is:

1. A down-draft sectional boiler having a horizontal flue extending through the upper portion thereof, and vertically-disposed flues leading from the combustion chamber beneath the grate to said horizontal flue; substantially as described.

2. A down-draft sectional boiler provided with a grate, a hollow water crown extending over said grate and downwardly on each side of the combustion chamber beneath the grate, and vertical flues leading from the combustion chamber beneath the grate to horizontal flues which extend longitudinally of the boiler over said water crown; substantially as described.

3. A down-draft sectional boiler provided with water legs that are connected by water bases, a grate arranged over said water bases, means for causing the fire to pass downwardly through said grates and play on said water bases, and vertical flues leading from the combustion chamber beneath the grate to horizontal flues that lead to a smoke pipe; substantially as described.

4. A down-draft boiler composed of sections having hollow water legs and hollow water bases connecting said legs, a hollow water crown extending downwardly on each side of the combustion chamber, and connected by hollow contracted webs to said water legs so as to produce vertical flues between the sections, depending portions of said crown terminating adjacent the water base to permit the fire to travel from the combustion chamber upwardly through said flues, and a horizontal flue extending over the hollow water crowns and communicating with the vertical flues; substantially as described.

5. A down-draft sectional boiler comprising a grate, a hollow water base arranged beneath the grate and connecting the water legs of the sections, and vertical flues leading from the combustion chamber underneath the grate to a horizontal flue above the grate; substantially as described.

6. A down-draft boiler composed of a plurality of sections placed together, the inter-

mediate sections of the boiler each consisting of water legs connected by a hollow water base, a hollow water crown extending downwardly on each side of the combustion chamber and connected to said water legs by contracted hollow webs so as to form vertical flues between the sections, the depending portions of each crown terminating adjacent the water base and each of said sections being provided above the water crown with a horizontal flue opening that communicates with said vertical flues; substantially as described.

7. A down-draft sectional boiler provided with water legs and a water base, a grate arranged above the water base, a hollow water crown extending over the grate and downwardly on each side of the combustion chamber, a horizontal flue extending longitudinally of the boiler above said crown, and means for causing the fire to travel downwardly through the grate and thence upwardly between the depending portions of the crown and the water legs to the horizontal flue; substantially as described.

8. A sectional boiler having a hollow water grate that is connected to the inner wall of a water chamber in the front section, a section located at the rear of the front section and provided with a water chamber to the inner wall of which the rear end of the water grate is connected, and removable devices in the outer walls of the water chambers of said sections located adjacent the points at which

the water grate is connected to the inner walls of said chambers; substantially as described.

9. A sectional boiler provided with a hollow water grate composed of a plurality of sections that are connected by means of nipples to the inner walls of water chambers in the front and rear sections of the boiler, and removable plugs in the outer walls of the water chambers in said front and rear sections located in alignment with said nipples; substantially as described.

10. A boiler composed of a plurality of sections each of which is provided at its upper end with a steam dome and at its lower end with a water base, water connections between said water bases, water connections located below the domes for connecting the upper ends of the sections with each other, a hollow water grate connected to water chambers in the front and rear sections of the boiler, means for creating a down-draft through said grate, and vertical flues leading from the combustion chamber beneath the grate to a horizontal flue above the grate; substantially as described.

In testimony whereof I hereunto affix my signature in the presence of two witnesses, this sixth day of February 1907.

ELIJAH M. BOSLEY.
